UNITED STATES PATENT OFFICE.

WILLIAM EDWARDS, OF EASTON, PENNSYLVANIA.

UMBRELLA.

959,127.

Specification of Letters Patent.

Patented May 24, 1910.

Application filed June 11, 1909. Serial No. 501,616.

To all whom it may concern:

Be it known that I, WILLIAM EDWARDS, a citizen of the United States, residing at Easton, in the county of Northampton and State of Pennsylvania, have invented certain new and useful Improvements in Umbrellas; and I do hereby declare the following to be a full, clear, and exact description of the invention, such as will enable others skilled in the art to which it appertains to make and use the same.

My invention relates to improvements in umbrellas and has for its object to provide for readily replacing broken ribs without removing the cover of the umbrella; also to provide for prolonging the usefulness of the umbrella by preventing the collapsing of the frame.

Other objects and advantages will be apparent from the appended description.

The invention consists of certain features or instrumentalities, substantially as herein-after fully disclosed and defined by the claims.

In the accompanying drawings forming part of this invention and illustrating the preferred embodiment of my invention, Figure 1 is a sectional elevation of said invention. Fig. 2 is a vertical section of the notch member. Fig. 3 is a horizontal section produced through Fig. 2. Fig. 4 is a detached plan view of the notch member. Fig. 5 is an inverted detail view of one of the adjunctive parts of the invention which is applied to the ribs and stretchers, a portion of one of the ribs being shown in connection therewith. Fig. 6 is a transverse section produced on the line 6—6, of Fig. 5.

Referring to the drawings in which similar reference numerals designate corresponding parts throughout the several views, 1 indicates a rod or handle to which is applied, near its upper end, a notch consisting of a solid or thickened portion 4, suitably applied or secured to said rod or handle, and a cap 17 fitting upon said solid portion 4 and suitably held or fixed thereto by a screw 15 passing through said cap and engaging said solid portion. A runner 4^a is also applied to or receives the staff or handle 1, said runner having an extended sleeve portion 4^b, also receiving said handle or rod, said sleeve extension having slidably arranged thereon, an additional sleeve 2 adapted for engagement with a latch 3 suitably seated in the rod or handle 1 for the

retention of the runner in an elevated position upon said rod or handle 1, as when the umbrella is in open position.

Ribs 9 and stretchers 8, pivoted to said ribs in the usual way at 10, are employed in connection with said notch and said runner, the connection between which ribs and stretchers and said notch and runner being effected as will be next described. The ribs 65 9 are each provided with a sleeve 11 the inner end of said sleeves being provided with a ball or spherical terminal 7, the notch being provided with a circular arrangement of sockets 6 receiving the ball or spherical 70 terminals 7, said sockets communicating with slots 5 formed in the notch, said slots receiving rectangular-like extensions of the sleeves 11 when the umbrella is in a folded position, as is apparent from Fig. 2. The 75 cap member 17 has in its lower edge also a circular arrangement of slots 18 which are adapted to register with the slots 5 of the member 4 and are also adapted to receive the rectangular portions of the sleeves 11. 80 Said cap is adapted to retain the ball or spherical terminal 7 of the sleeve members 11 in effective position in the sockets of the notch, said cap being movable, after the release of the screw 15, when it may be desired 85 to detach any of the ribs from the notch. Also applied to the ribs 9 at their outer ends is a like sleeve 11^a provided with like balls or spherical terminals, said sleeves also having loops 16^a, the sleeve members 11 also 90 having their rectangular portions provided with apertures 16, said apertures and loops being designed to receive the fastening means or threads for securing or fastening the cover upon the ribs. From this arrangement 95 it will be noted that in event of breaking or damaging any one of the ribs, the same may be removed readily without detaching the cover, and accordingly be replaced by a substitute rib or ribs, the impaired rib being readily removable from the sleeve portions and the new or effective rib inserted into said sleeves. Also it is noted that a damaged or broken rib which may be capable of further use may be filed off at 100 one end and be further used by the employment of the sleeve members, by suitably adjusting said sleeve members with relation to said rib for the proper retention and stretching of the cover in place thereon, as is 105 readily apparent. The ribs 9 are approximately U shaped in cross section as seen in

Fig. 6, as is also the sleeve members, the inner edges of said sleeve members being upturned within the said ribs for their retention as at 12 and whereby said sleeves 5 may be readily removed and replaced as occasion may require, or the ribs removed from said sleeves. The runner member 4^a is also provided with a circular arrangement 10 of sockets, slots and cap member 17^a, similar to those described in connection with the notch member for the reception and retention in connection with said runner of the inner spherical terminated ends 7^a of the stretchers 8, as seen in Fig. 1, and whereby 15 said stretchers may be readily disconnected from said runners.

What I claim is:—

1. A device of the character described comprising a notch having a circular arrangement of sockets therein, and a corresponding arrangement of slots therein in communication with said socket, a cap member applied to said notch having a circular arrangement of slots in its lower edge adapted 20 to register with the aforesaid slots, means for the retention of said cap upon said notch, ribs, sleeve members having spherical terminals received by said sockets and rectangular portions adjacent to said terminals received by the slots of said notch and cap, said sleeve members receiving said ribs at their inner ends, additional sleeves applied to said ribs at their outer ends, and means on both sleeve members for the reception 25 of the attaching means for a cover.

2. A device of the character described comprising a handle, a notch applied to said handle and having a socket and a slot communicating with said socket, a cap applied 30 to said notch and having a slot in its lower

edge registering with the slot of said notch, means for the retention of said cap upon said notch, a runner applied to said handle, said runner having a like socket and slot therein, a cap applied to said runner also 45 having a slot in its lower edge registering with the slot of said runner, a sleeve member having a spherical terminal received by the socket of said notch, said sleeve member having a rectangular portion adjacent to this spherical terminal, received by the slot of said notch, a rib received by said sleeve member, a stretcher connected to said rib at one end and having its opposite end provided with a spherical terminal received 50 by the socket of said runner, said stretcher also engaging the slot of said runner, an additional sleeve member applied to said rib, a cover and means on said sleeve members for the retention of said cover. 55

3. In a device of the character described, the combination with a staff, a notch mounted on said staff having sockets and slots therein, and a cap for said notch; of ribs, a sleeve mounted on each end of said ribs, 60 said sleeves having spherical terminals on the ends thereof, the spherical terminals of the inner sleeves engaging the sockets of said notch, said cap having slots therein registering with said other slots, means to retain said cap member on said notch, a cover and means on both sets of sleeves for attaching said cover thereto. 70

In testimony whereof I have signed my name to this specification in the presence of 75 two subscribing witnesses.

WILLIAM EDWARDS.
